UNITED STATES PATENT OFFICE.

ISAAC NEWTON ROGERS, OF NEW YORK, N. Y.

SPRING-LATCH FOR SCUTTLES, &c.

SPECIFICATION forming part of Letters Patent No. 333,674, dated January 5, 1886.

Application filed April 2, 1885. Serial No. 161,009. (No model.)

To all whom it may concern:

Be it known that I, ISAAC NEWTON ROGERS, a citizen of the United States, and a resident of New York city, county and State of New York, have invented a new and useful Improvement in Spring-Latches for Fastening Scuttles, Doors, &c., of which the following is a specification.

The object of my invention is to produce an automatic and simple spring-latch fastener for fastening scuttles or doors used for closing openings leading onto the roofs of buildings, or for fastening ordinary doors.

Referring to the drawings, Figure 1 is a sectional elevation of a scuttle embodying my invention. Fig. 2 is a sectional end view of the same. Fig. 3 is a bottom view of the same. Figs. 4, 5, and 6 are views showing my improved fastener attached or used on a door.

20 A is the frame-work of the scuttle or opening leading to the roof of building.

B is the cover, hinged to the frame A by hinge D or any other suitable contrivance.

E is a metallic latch, made of any metal, and 25 consisting of the long arm e, with hook e', and the short arm e''. This latch is pivoted and held to the under side of the lid B by means of the bearings e' e'', which are provided with recesses f f, for the admission or insertion of 30 the trunnions g g on the latch E, upon which the said latch oscillates. These bearings e' e'' are fastened to the lid by screws or bolts H H.

I do not confine myself to any particular number of latches to be used on doors or covers.

35 The latch E is held in position shown in Fig. 1 by the spring e', placed between the lever J and the door or cover B, the object of which spring is to throw the arm e of the latch forward so that the device will automatically 40 latch itself.

J is a lever hinged at one end to the under side of the lid B by hinges K. The other end of said lever is secured to the short arm e'' of the latch by a bolt, L. This lever J may consist of a narrow strip of wood or a wide board, 45 as shown in Figs. 3 and 4, the inside of lever to be covered with sheet metal.

M is a lug or catch fastened on the inside of frame A, just opposite long arm e of the latch. This lug is used for the hook e' to engage with 50 when the lid or door is closed. (See Fig. 1.)

Some buildings are provided with a door, W, (see Fig. 5,) instead of a scuttle-cover, as shown in Fig. 1. In these cases I attach my fastener to the door, as shown in said figure, 55 wherein the same principle is observed with such slight mechanical changes as the location suggests.

All that is necessary to open the lid B or door W is to press against the lever J, which 60 will cause the latch to relieve its hold on the lug M. To close the lid or door, simply let the same in place and the latch will automatically lock itself, as shown in Figs. 1, 4.

By this arrangement a durable and secure 65 automatic fastener is produced for scuttles or roof-openings, and all doors leading from buildings to the street.

What I claim is—

In a spring-latch, the combination, with the 70 latch E, having a long arm, e, provided with hook e', and a short arm, e'', of the lever J, hinged to the door, the bolt L, connecting said lever and short arm, the spring e', and the beveled lug M, substantially as and for the purpose set forth.

ISAAC NEWTON ROGERS.
